UNITED STATES PATENT OFFICE.

LOUIS F. DUCK, OF DE KALB, ILLINOIS.

EXPLODING TOY BOMB.

1,388,807.

Specification of Letters Patent. Patented Aug. 23, 1921.

Application filed December 13, 1919. Serial No. 344,641.

To all whom it may concern:

Be it known that I, LOUIS F. DUCK, a citizen of the United States, residing at De Kalb, in the county of De Kalb and State 5 of Illinois, have invented new and useful Improvements in Exploding Toy Bombs, of which the following is a specification.

This invention is an improved exploding toy bomb adapted for use in connection with 10 a paper cap, one or more, and to cause the explosion of the cap to throw a feathered plug up into the air and which feathered plug then descends and whirls while descending, so as to afford amusement as well 15 as to make a loud explosion, the invention consisting in the construction, combination and arrangement of devices hereinafter described and claimed.

In the accompanying drawings:

20 Figure 1 is a vertical sectional view of my improved toy aerial bomb showing the same before the explosion occurs.

Fig. 2 is a similar view of the same after the explosion occurs.

25 The body 1 of the bomb is here shown as substantially spherical and with a neck 2 in the upper side, the neck being provided with a bore 3 in the bottom of which one or more paper caps, indicated at 4, are to be placed.

30 A plug 5 is fitted snugly and frictionally in the bore and is provided with an upwardly extending shaft 6 on which is a disk 7. A head 8, which is preferably made of rubber, is slidably engaged upon the shaft 35 above the disk 7 and engages against said

disk, and is provided in the upper side with three or any suitable number of feathers 9 which are so arranged as to cause the plug to whirl when it passes through the air.

When the bomb has been provided with 40 the paper cap or caps and the plug has been inserted in the bore the bomb should then be thrown up into the air or dropped from a height onto a hard pavement or other surface. The force of the impact causes the 45 plug and the bomb body to explode the caps with a loud report, the force of the explosion serving to throw the shafted and feather headed plug up into the air, the plug first and the feathers downward and after thus 50 ascending the plug reverses and descends to the ground with the feathers uppermost and also describing whirling motion, caused by the feathers, so that the bombs serve to 55 also give an interesting, an amusing aerial display as well as to cause the loud explosion.

* Having thus described my invention, I claim:

An aerial toy bomb comprising a relatively 60 heavy base formed in its top with a recess for the reception of caps, a plunger slidably engaged within said recess and carrying at its upper end a shaft formed intermediate its ends with a disk, and a projectile member including a base slidably engaged upon the upper end of said shaft in abutting relation to the disk and carrying guide feathers.

In testimony whereof I affix my signature.
LOUIS F. DUCK.
